PANEL FOR LAUNDRY APPARATUS

William H. Welcher, North Syracuse, and Stuart G. Mundt, Syracuse, N. Y., assignors to Easy Washing Machine Corporation, Syracuse, N. Y., a corporation of Delaware

Application September 6, 1952, Serial No. 21,358

Term of patent 14 years

(Cl. D49—1)

To all whom it may concern:

Be it known that we, William H. Welcher and Stuart G. Mundt, citizens of the United States of America, residing at North Syracuse, in the county of Onondaga and State of New York, and Syracuse, in the county of Onondaga and State of New York, respectively, have invented a new, original, and ornamental Design for a Panel for Laundry Apparatus, of which the following is a specification, reference being had to the accompanying drawings, forming part thereof, in which:

Figure 1 is a front elevational view of a panel for laundry apparatus, showing our new design;

Figure 2 is a longitudinal section taken on the line 2—2 of Figure 1;

Figure 3 is an enlarged transverse section taken on the line 3—3 of Figure 1;

Figure 4 is an enlarged transverse section taken on the line 4—4 of Figure 1; and

Figure 5 is an enlarged transverse section taken on the line 5—5 of Figure 1.

We claim:

The ornamental design for a panel for laundry apparatus, substantially as shown.

WILLIAM H. WELCHER.

STUART G. MUNDT.
